(57) **CLAIM**

The ornamental design for the printer, as shown and described.

DESCRIPTION

FIG. 1 is a perspective view of a first embodiment of a printer showing our new design;

FIG. 2 is a second perspective view of the first embodiment of the printer;

FIG. 3 is a front view of the first embodiment of the printer;

FIG. 4 is a rear view of the first embodiment of the printer;

FIG. 5 is a right view of the first embodiment of the printer;

FIG. 6 is a left view of the first embodiment of the printer;

FIG. 7 is a plan view of the first embodiment of the printer;

FIG. 8 is a bottom view of the first embodiment of the printer;

FIG. 9 is a perspective view of a second embodiment of a printer showing our new design;

FIG. 10 is a second perspective view of the second embodiment of the printer;

FIG. 11 is a front view of the second embodiment of the printer;

FIG. 12 is a rear view of the second embodiment of the printer;

FIG. 13 is a right view of the second embodiment of the printer;

FIG. 14 is a left view of the second embodiment of the printer;

FIG. 15 is a plan view of the second embodiment of the printer; and,

FIG. 16 is a bottom view of the second embodiment of the printer.

(Continued)

The evenly spaced broken lines shown in the drawings represent portions of the printer that form no part of the claimed design. The dot-dash broken lines depict the bounds of the claimed design.

1 Claim, 16 Drawing Sheets
